UNITED STATES PATENT OFFICE

JAMES BARKER, OF KALAMAZOO, MICHIGAN

LOOSE-LEAF BINDER

Application filed February 16, 1928. Serial No. 254,826.

This invention relates to loose leaf binders and more particularly to improvements in the construction thereof tending to simplify and render the same more efficient generally.

5 The invention contemplates an improved locking bar construction which may be economically manufactured and quickly and easily assembled. This invention also contemplates permanently attaching the lifting or transfer bars to the fly leaves as for instance by binding the lifting bar with the fly leaf.

The several objects, advantages and novel details of construction of this invention will be made more apparent as this description proceeds, especially when considered in connection with the accompanying drawings wherein

Figure 1 is a fragmentary perspective view 20 of a loose leaf book constructed in accordance with my invention, one of the covers being unlocked and moved to open position.

Figure 2 is a plan view partly in section of the locking bar construction.

25 Figure 3 is an enlarged fragmentary view of a portion of the structure illustrated in Figure 2 with the parts in different position.

Figure 4 is a detail sectional view taken 30 substantially on the plane indicated by line 4-4 in Figure 2, and

Figure 5 is a fragmentary perspective view 35 of the locking bar mechanism removed from the guide.

40 By reference to Figure 1 it will be noted that there is illustrated a loose leaf book comprising a back 10 connecting cover members 11. The reference characters 12 and 13 indicate lifting or transfer bars. In accordance with the usual practice, each transfer bar is provided with one or more impaling posts 14 which project through openings in the sheets 15, the posts on one bar being out of alignment with the posts on the other bar.

45 It will be noted that these transfer bars 12 and 13 are separate from the back 10 and covers 11 and in the present instance these transfer bars are secured to the respective fly leaves 16 by being bound therewith as indicated at 17. The reference character 18 in-

dicates locking posts projecting through the transfer bars 12 and 13 respectively and adapted to be engaged by the locking bar construction carried by the covers 11, in the customary manner. Inasmuch as the locking bar construction carried by each cover 11 is identical, a description of one will suffice. Associated with each cover is a plate member 19 having a return-bent portion 20 and struck-up ears 21 providing a guide-way having a locking bar 22. The one end of this locking bar extends beyond the guide-way 23 and is bent at an angle to provide a thumb-piece or handle 24 by means of which locking bar 22 is moved longitudinally of its guide way.

The reference character 25 indicates locking pins adapted for engagement in the sockets 18' formed in the ends of locking posts 18 when moved across openings 26 formed in the guide-way 23. In their inoperative position these locking pins are withdrawn to a point within the guide way as indicated in Figure 3.

In order to provide a simple but efficient means of securing the locking pins 25 to locking bar 22 I provide the latter with recesses 27 into which the angularly bent end 28 of each locking pin is adapted to extend. Therefore in assembling the structure the ends 28 of the locking pins are lodged in the recesses 27 and these assembled parts are then placed in the guide way and by reason of the position of the locking pins between the locking bar 22 and the wall of the guide way disengagement of the locking pins with reference to the locking bar is prevented.

The reference character 29 indicates a keeper rigidly secured in the guide way 23 as for instance by means of a bolt 30. This keeper 29 is provided with latch recesses 31 and 32 engageable by means of a latch 33 carried by locking bar 22. Latch 33 may be conveniently and economically formed by reducing the end of bar 22 as clearly illustrated in the drawings to thus provide a latch member which is relatively resilient and one which may be snapped into engagement with either of the two latch recesses of keeper 29. When latch 33 is in engage-

ment with latch recess 31 locking pins 25 are in their operative position but when latch 33 has been released from latch recess 31 locking bar 22 may then be moved longitudinally until latch 33 snaps into engagement with latch recess 32. This position of the parts is illustrated in Figure 3 and by reference to this figure it will be noted that the locking pins are in a position where they project slightly into the openings 26 for engagement in the grooves formed in the locking posts adjacent the sockets therein. Thus the locking pins in this position form stops for positioning the locking posts within the openings in the manner clearly brought out in my co-pending application, Serial No. 163,234, filed January 24, 1927.

As a simple but effective means of releasing latch 33 I provide a key member 34 adapted to be inserted in the guide way 23 parallel to one surface of keeper 29. The keeper is preferably formed with one or more slots 35 with which ribs 36 on the key member 34 engage. Upon the insertion of the key member one longitudinal edge thereof engages the bevelled end 37 of latch 33 and springs this latch out of engagement with the latch recess 31. It is then possible to move locking bar 22 longitudinally until the latch has been snapped into engagement with latch recess 32.

With this construction the locking bar is positively secured in its operative position and is prevented from being completely withdrawn. Obviously latch recess 31 could be eliminated and the bar 22 held in its operative position merely by the friction between the parts.

While an embodiment of the invention has been illustrated and described herein somewhat in detail it will be readily apparent that various changes in many of the details of construction herein illustrated may be resorted to without departing from the spirit and scope of this invention and to this end reservation is made to make such changes as may come within the purview of the accompanying claims.

What I claim as my invention is:-

50 1. In a looseleaf binder, a guide, a locking bar slidable therein, a latch carried by said locking bar, a keeper having a plurality of latch recesses engageable by said latch and means for disengaging said latch from one of said latch recesses.

60 2. In a loose leaf binder, a locking bar construction comprising, a guide, a bar slid- able therein, one end of said bar being formed into a resilient latch, a keeper fixed to said guide and engageable by said latch and means for springing said latch to disengage the same from said keeper, said means includ- ing a member engageable in a slot in said keeper.

65 3. In a loose leaf binder, a locking post,

a locking pin engageable therewith and a control means therefor including a slidable bar carrying said locking pin, a keeper having a plurality of latch recesses and a resilient latch carried by said control means engageable with the latch recesses in said keeper.

4. In a loose leaf binder, a locking bar construction comprising a guide, a slidable bar formed with a recess and a locking pin having a portion extending into said recess and held therein by engagement with said guide.

5. In a loose leaf binder, a locking bar construction comprising a guide, a bar slid- able therein and formed with a recess and a locking pin provided with an angularly bent end engaging said recess and held in place by engagement with said guide.

6. In a loose leaf binder, a guide, a bar slidably mounted in said guide, locking pins carried by said bar, a keeper provided with latch recesses, a resilient latch carried by said bar engageable with said latch recesses and a key member insertable in said guide for springing said latch out of engagement with one of said recesses.

7. In a loose leaf binder, a locking bar construction including a guide, a slidable bar mounted in said guide, and a locking pin detachably engageable with said sliding bar, said locking pin being held in engagement with said bar by said guide.

8. In a loose leaf binder, a locking bar construction including a slidable bar having a latch, and a keeper having portions selectively engageable by said latch whereby said bar may be locked in one of a plurality of spaced positions.

9. In a loose leaf binder, a locking bar construction including a slidable bar having a latch, a keeper engageable by said latch, said keeper having a keyway, and a key engageable in the keyway in said keeper for forcing said latch from engagement with said keeper.

In testimony whereof I affix my signature.
JAMES BARKER.
